UNITED STATES PATENT OFFICE

131,399

DESIGN FOR A PLOW

Lorin Forgy, Beloit, Kans.

Application June 16, 1941, Serial No. 101,482

Term of patent 14 years

To all whom it may concern:

Be it known that I, Lorin Forgy, a citizen of the United States, residing at Beloit, in the county of Mitchell and State of Kansas, have invented a new, original, and ornamental Design for Plows, of which the following is a specification, reference being had to the accompanying drawing, forming part thereof.

Fig. 1 is a side elevational view of a plow, showing my new design.

Fig. 2 is a top plan view thereof.

Fig. 3 is an elevational view, showing the opposite side of Fig. 1.

Fig. 4 is a rear elevational view.

I claim:

The ornamental design for a plow, as shown.

LORIN FORGY.
